UNITED STATES PATENT OFFICE.

OSCAR E. BACKUS, OF WAUKESHA, WISCONSIN.

BUTTON.

1,127,847.

Specification of Letters Patent.

Patented Feb. 9, 1915.

Application filed March 23, 1914. Serial No. 826,718.

To all whom it may concern:

Be it known that I, OSCAR E. BACKUS, of Waukesha, Wisconsin, have invented a Button, of which the following is a specification.

This invention relates to buttons or garment fastenings, and the object which I have in view is to produce a button or like fastening which can be readily attached to 10 the garment or fabric without sewing.

A further object of the invention is to provide means whereby the button can be readily attached to any fabric and detached therefrom again if desired by a simple manipulation and without in any way injuring the fabric.

The essential principle of my button consists in providing it with a disengageable loop or bail which has a sharpened point 20 adapted to be inserted in the fabric to which it is to be attached and which is thereafter adapted to be engaged with the body of the button.

More exactly, the nature of my invention 25 may be ascertained from the accompanying drawings illustrative thereof, taken in connection with the following description of said drawings; and the parts or combinations which I claim as new are more 30 particularly set forth in my claims. Said drawings illustrate three forms or embodiments of my invention, the same being drawn to a scale somewhat larger than the ordinary or natural size, and herein—

35 Figure 1 is a bottom plan-view of the body of the first form of button, the engaged position of the bail being indicated by dotted lines; Fig. 2 is an axial section of the button in the position of use, on plane 40 2; Fig. 3 is an axial section on the plane 3, the bail being shown in elevation except one end thereof; Fig. 4 is a bottom plan-view showing the bail in disengaged position, ready for engaging it with the fabric; Fig.

45 5 is a bottom plan-view of the body of the second form of button, in which the bail is adapted to be completely disengaged from the body; Fig. 6 is a bottom plan-view showing the bail with one end disengaged; Fig. 50 7 a perspective view of the bail of this form; and Fig. 8 is a bottom plan-view of the third form of button.

The reference letters refer each to the same part in each figure of the drawing.

55 Considering first the form of button shown in Figs. 1 to 4 inclusive, the body

of the button as exhibited comprises a cup-shaped body-plate *a*, covered with fabric, leather, etc., *b*, and the bottom-plate *c*, between which and the edge of the plate *a* 60 the fabric is confined in the manner shown, but this has no relevancy to my invention and the body of the button may be formed in any manner whatever, provided it has the two plates *a* and *c* or their equivalent. Said 65 bottom-plate *c* is made of spring-metal and is perforated by two holes *d*, which lie on the same diameter and are adapted to receive the two shanks of the bail *e*. The bail *e* as shown is made in the form of a loop, 70 which is adapted to engage a portion of the material to which the button is to be attached, and one lug or shank of this bail has its end turned at right-angles, as shown at *f*, in the plane of the bail, and then subsequently again at right-angles to the plane 75 of the bail as shown at *g*; the distance between the axis of the shank and the end portion *g* being very short so that the bail can be turned from the position shown in full 80 lines shown in Fig. 3 to that shown in dotted lines when the other end of the bail is not engaged. The other end *h* of the bail is also turned at right-angles to the shank thereof and in the plane of the bail, and is 85 pointed so as to enable it to readily pierce the fabric or goods to which the button is to be attached. There are formed in the bottom-plate *c* two cuts *i* and *j*, which meet at one side of the hole *d*, through which the 90 shank of the bail having the pointed end *h* passes; my invention does not require any particular or necessary shape of these cuts *i* and *j*, but they are so formed that their distant ends approach one another as shown, 95 sufficiently to form a flexible spring-tongue *k*. This spring-tongue, it will be obvious, normally lies in the plane of the body-plate *c*.

The mode of operation of this form of my 100 button is as follows: In the manufacture of the button the bent end *f*, *g*, of the bail *e* is confined between the plates *a* and *c*, the shank *e* passing through the hole *d* and thereafter is nonremovable. The other end *h* of the bail 105 is, however, insertible into and removable from its hole *d* by manually depressing the spring-tongue *k*. When inserted in the position shown in Fig. 3 it will be clear that the edge of the spring-tongue forms an 110 abutment to keep it in the hole, and therefore to hold the bail in the dotted line po-

sition of Fig. 1, or full line positions of Figs. 2 and 3. Now if the spring-tongue *k* be manually depressed, the bail can be turned about the upper hole *d* of Fig. 1 as 5 a bearing, as illustrated in Fig. 4, the lower shank and end *h* being released from engagement with the bottom-plate *c* and coming outside thereof. The bail can now be turned into the position shown in dotted 10 lines in Fig. 3, that is to say, about the straight end *g* as an axis, but it cannot be removed or fall out from its place. The pointed end having been inserted into and engaged with a sufficient portion of the fabric is turned down again into the position of 15 Fig. 4, and being depressed can be rotated so as to engage under the plate *c* again, and when the shank is in the socket-hole *d* the spring-tongue *k* snaps back into place holding 20 it there.

The second form of button illustrates the same principle, with, however, the added provision of means whereby the bail can be removed altogether if it is desired to do so. 25 In this case the cuts *i* and *j* are duplicated, one of each such cuts being formed symmetrically with respect to the other, thus providing a spring-tongue *k* for each of the two socket-holes *d*. The bail *e'* is identical 30 in respect to the bent portions *f* and *g* on one end to that previously shown, and it might be effectively in all respects made identical, but in this case between the shank and the pointed end *h* I have provided 35 a right-angled offset *m*, whereby a shoulder is provided to enable the shank more effectively to engage under the plate *c* on the edge of the hole *d*. As previously, disengagement of the pointed end *h* is first effected 40 by depressing the corresponding spring-tongue *k* and rotating the bail about the opposite shank. Should it now be desired to disengage the other end also from its socket, the bail is rotated sufficiently so 45 that its straight portion *g* completely underlies the left-hand tongue *k* of Figs. 5 and 6, and it then can be released by pulling on the bail, which will cause the tongue *k* to yield outwardly sufficiently to enable the 50 end *g* to slide out.

In the third form of button the body is made the same as in Figs. 5 and 6 but the bail *e''* is made in a different form from either of the foregoing, the shanks thereof having their ends *g'* turned first at right angles from the plane of the bail in opposite or symmetrical directions away from the spring-tongues as shown. In this form of button either end of the bail may be detached independently of the other, as is the case with only one end in the foregoing forms, or both may be detached simultaneously by pressing both of the spring-tongues *k* and rotating the bail with the 60 same fingers that press the tongues. 65

Of course there will be other ways and shapes of bail and plate by which the same principle may be carried out, and I naturally consider these included in the scope of my invention so far as included in my 70 claims, the above being merely shown as illustrations of the general principle involved.

Having thus described my invention, what I claim as new and desire to secure by Letters Patent is:

1. The combination of a button-body comprising two plates spaced apart to leave a flat open space between them, one of said plates having a pair of socket-holes adapted 80 to receive the shanks of a loop-shaped bail and having a spring-tongue the end of which forms one side of one of said holes when in normal position and can be depressed so as to leave said side of the hole 85 open; and a loop-shaped bail having two parallel shanks, one of which engages in the other hole and has means lying between the two plates for holding it in said hole whereby the bail can be turned about said 90 shank and hole as a pivot, and the other shank having its end bent at right-angles and pointed, and adapted to be received in the other hole of which the spring-tongue forms one side. 95

2. The combination of a button-body comprising two plates spaced apart to leave a flat open space between them, one of said plates having a pair of socket-holes adapted to receive the shanks of a loop-shaped bail 100 and having spring-tongues the ends of which form one side of the respective holes when in normal position and can be pressed out of the plane of the plate so as to release the shank confined in the corresponding 105 hole; and a loop-shaped bail having two parallel shanks adapted to engage in said holes, one of said shanks having its end bent at right angles and pointed and adapted to be released from its hole by depressing the corresponding spring-tongue whereby the bail can be rotated about the axis of the 110 other shank, and the other shank having its end bent at right angles to the plane of the bail and thereby confined between the two 115 plates but adapted to be released therefrom when the bail has been turned in the manner aforesaid until said bent end lies entirely under the second spring-tongue whereby the 120 spring-tongue can be deflected by pulling on said bail. 125

3. The combination of a button-body comprising two plates spaced apart to leave a flat open space between them, one of said plates having a pair of socket-holes adapted 125 to receive the shanks of a loop-shaped bail and having spring-tongues the ends of which form one side of the respective holes when in normal position and can be pressed out of the plane of the plate so as to release 130

the shank confined in the corresponding hole; and a loop-shaped bail having two parallel shanks adapted to engage in said holes, said shanks having their ends bent at right angles and adapted to be released from their sockets by depressing one of said spring-tongues and rotating the bail.

In witness whereof I have hereunto set my hand in the presence of two witnesses.

OSCAR E. BACKUS.
